US00D890485S

(12) **United States Design Patent** (10) **Patent No.:** **US D890,485 S**
(45) **Date of Patent:** **** Jul. 21, 2020**

(54) **SHOE**

(71) Applicant: **adidas AG**, Herzogenaurach (DE)

(72) Inventors: **Jacques Perrault**, Portland, OR (US);
Andrew Jacob Schneider, Portland,
OR (US); **George Alan Robusti**,
Portland, OR (US)

(73) Assignee: **adidas AG**, Herzogenaurach (DE)

(**) Term: **15 Years**

(21) Appl. No.: **29/669,903**

(22) Filed: **Nov. 12, 2018**

(51) LOC (12) Cl. **02-04**

(52) U.S. Cl.

USPC **D2/947**; D2/959; D2/960

(57)

CLAIM

The ornamental design for a shoe, as shown and described.

DESCRIPTION

FIG. 1 is a front view of a shoe showing the claimed design;
FIG. 2 is a rear view thereof;
FIG. 3 is a left side view thereof;
FIG. 4 is a right side view thereof;
FIG. 5 is a top view thereof;
FIG. 6 is a bottom view thereof;
FIG. 7 is an enlarged view of a portion of FIG. 3; and,
FIG. 8 is an enlarged view of another portion of FIG. 3.
The dashed broken lines in the figures show portions of the
shoe that form no part of the claimed design.

The dot-dash broken lines in the figures and the areas within
the dot-dash broken lines show portions of the shoe that
form no part of the claimed design.

The dot-dot-dash broken lines in the figures show boundaries
that form no part of the claimed design.

1 Claim, 8 Drawing Sheets
